Inventor:

Thomas A. Marsh.

by Augu. Swan Atty.

UNITED STATES PATENT OFFICE.

THOMAS A. MARSH, OF CHICAGO, ILLINOIS, ASSIGNOR TO GREEN ENGINEERING COMPANY, OF EAST CHICAGO, INDIANA, A CORPORATION OF ILLINOIS.

STOKER FURNACE.

Application filed January 29, 1923. Serial No. 615,485.

This invention relates to chain grate stokers and consists in the matters herein-after described and more particularly set forth in the appended claim.

5 In the accompanying drawings—

Fig. 1 is a longitudinal vertical sectional view of a stoker furnace embodying the features of my invention; and

10 Fig. 2 is a transverse vertical sectional view taken on line 2—2 of Fig. 1.

In the drawings, I have shown a furnace equipped with a chain grate 1 having upper and lower runs or leads 2 and 3. Said grate 1 extends into the combustion chamber of 15 the furnace through the front wall of its setting with the rear or tail end of the grate terminating short of the bridge wall 4 to provide a vertical ash discharge passage as in furnaces of this general kind. At the 20 front of the furnace is a fuel hopper 5, through which fresh or green fuel is fed on the upper lead 2, which carries the fuel in a layer through the combustion chamber, as apparent.

25 The grate 1 extends horizontally between the side walls 6, 6 of the furnace setting, as shown in Fig. 2, and each of these walls includes a plurality of upright metal stools 7, 7. The stools 7, 7, in each wall, are 30 laterally spaced apart the same distance with the stools in one wall aligned with the corresponding stools in the opposite wall. The stools 7, 7 rest on the foundation 8 of the furnace setting. Extending between 35 and secured to the stools in each wall are housings or casings 9. These form with the stools between which they extend vertical air ducts 10 at the sides of the grate 1, as shown in Fig. 2.

40 The space between the grate leads 2, 3 is divided into a plurality of compartments 11, 11, equal in number to the ducts 10 at one side of the grate. These compartments open at their ends into the ducts 10, 10. The compartments 11 are formed by cross-members 45 12, 12 aligned with and supported by the associate stools. Skids or rails 13, 13 extend lengthwise of the upper lead 2 beneath the same and support said upper lead. Said skids are supported by the cross-members 12, 12. Air seals between the compartments 11, 11 along the upper and lower edges of the cross-members 12, 12 are formed

by shoes 14, 15, associated with said members 12 and bearing against the respective leads 55 in the manner shown in the drawings.

The lower lead 3 rides on skids or rails 16, 16. These are supported by cross-members 17, 17 below said rails and aligned with the upper members 12, 12, as shown in Fig. 60 1. Shoes 18 are under the lower lead, above the cross-members 17, 17, to provide air seals along the under side of the lower lead between the compartments 11.

Under the lower lead 3 is the main air 65 supply conduit 19. This is common to all the vertical ducts 10, 10 and supplies forced draft thereto. Hinged dampers 20, 20 regulate the supply of air to the ducts 10 from the conduit 19.

To catch the siftings and droppage caught by the lower lead 3 and passed through its openings, I provide a plurality of collecting hoppers 21, 21 beneath the lower lead, as shown in Fig. 1. These hoppers 21, 21 are so arranged that there is a 70 hopper below each compartment 11. The hoppers have discharge chutes 22, 22 and these lead to the ash collecting chamber below the furnace and may be provided with 75 suitable control gates 22^a, as shown. The hoppers 21, 21 are in the main supply conduit 19, but the forced draft therein is prevented from reaching the compartments 11, 11 through the lower lead 3 from below by 80 the hoppers having their walls close the compartments below said lower lead. This may be done by having the front and rear 85 walls of the hoppers extended to the cross-beams 17, 17 and their side walls secured to 90 plates 23, 23 above the dampers 20, as shown in Fig. 2.

The main conduit 19 may be supplied with air in any suitable manner to deliver forced draft to the ducts 10. The means 95 shown in Fig. 1 includes an electric motor 24 operating a blower 25, which opens into the conduit 19 through its front wall 26. The latter may be aligned and secured to the stools 7, 7 at the front of the furnace.

To operate the dampers 20, 20, I provide telescoped shafts 27, 27^a, 27^b, and 27^c, one for each set of the dampers. These are connected with their respective shafts by links 28, 28 and arms 28^a. The shafts 27, etc. are 100 accessible from the front of the furnace and

are there provided with hand levers 29, 29, one for each shaft, as shown, for operating them.

By the construction shown and described, 5 the droppage collecting or supporting floor heretofore provided below the lower lead is dispensed with and hoppers employed to collect the droppage from the several compartments. With hoppers, there is no building up of droppage in the compartments 10 because the hoppers are deep enough to take care of the accumulation. The hoppers also close the compartments from beneath the lower lead, and avoid the use of the floor 15 heretofore used. Other and further advantages of my invention will appear to those skilled in the art to which it relates.

I claim as my invention:

In a stoker, the combination of an end- 20 less chain grate having upper and lower leads, an upper set of cross-members dividing the space between said leads into a plu-

rality of transverse compartments open to both leads, skids beneath the lower lead and extending lengthwise thereof for supporting the same, a lower set of cross-members beneath said skids and arranged transverse thereto in vertical alignment with the cross-members of the upper set for supporting said skids, shoes bearing against said leads 25 at both sets of cross-members, ducts at the sides of the grate and opening into said compartments for supplying draft thereto, a main supply conduit beneath said lower lead and common to all of said ducts, and a 30 plurality of droppage collecting hoppers in the spaces between the lower cross-members, said hoppers being arranged one for each compartment and having outlets to discharge the droppage collected thereby. 40

In testimony that I claim the foregoing as my invention, I affix my signature, this 25th day of January, A. D. 1923.

THOMAS A. MARSH.
